UNITED STATES PATENT OFFICE.

DOUGLAS BLY, OF NEW YORK, N. Y.

IMPROVEMENT IN ARTIFICIAL LEGS.

Specification forming part of Letters Patent No. 57,666, dated September 4, 1866.

To all whom it may concern:

Be it known that I, DOUGLAS BLY, of New York, in the county and State of New York, have invented certain new and useful Improvements in Artificial Legs; and I do hereby declare that the following is a full and exact description thereof, reference being had to the accompanying drawings, making part of this specification.

Figure 1 is a central vertical section of my improved leg; Fig. 2, a plan of the foot, and showing more particularly the arrangement of the springs between the foot and leg; Fig. 3, a plan of a portion of the bottom of the foot, showing the toe-joint arrangement; Fig. 4, a perspective view of the link-connection of the foot and leg; Fig. 5, a perspective view of one of the springs.

Like letters of reference indicate corresponding parts in all the figures.

I obtained a patent, dated August 30, 1859, for an improvement in artificial legs, which consists, essentially, in the interposition of a rubber segment, forming a spring, between the foot and ankle portions. My present invention is an improvement on that device; and it consists, principally, in the employment of a series of springs instead of a solid segment arranged between the foot and ankle portions at suitable distances apart, said foot and ankle having a free universal motion.

As represented in the drawings, A is the foot, and B the leg, which, in general construction, do not differ essentially from the corresponding parts in common use, except the foot has an oblong or oval socket, C, and the leg a corresponding bearing, D, resting closely therein, these parts being formed concentric with the center of motion, so as to fit and work closely and compactly together, whatever relative positions they may assume in the act of walking.

The foot and leg are connected by two links, E E, which form the center of motion. These are connected closely in the manner clearly shown in Fig. 4, so as to allow the foot to flex freely in the leg in every direction, but still limit rotary action of the leg. This construction of the double links allows any amount of compression of the springs at once by the sliding of the links on each other as the leg and foot approach. Any turning motion of

the leg is further prevented by the oval or oblong form of the socket and bearing C D. The links are secured in place by nuts b b, or in any convenient manner.

I prefer to place the center of motion at some distance back of the center of the socket C, as clearly indicated in Figs. 1 and 2, in order to distribute the leverage properly upon the different springs. The leverage of the springs depends upon their distance from the center of motion. Some of the springs are placed at a greater and others at a less distance from the center of motion, to counterbalance the pressure which will be applied when in action. The pressure on the front spring in walking will be as much greater than on the others as the length of the foot from the center of motion is greater than that of the sides or heel from the same point. Thus the center of motion is located at such a position that the distribution of leverage upon the several springs will be in proportion, as nearly as can be, to the pressure that will be applied thereon in action.

A sufficient space is left between the bottom of the socket C and the bearing D to allow sufficient flexion in any direction. Instead of the employment of the solid block of rubber between the foot and ankle, as in my former patent alluded to, I use in my present device a series of separate springs, G G G, of any desirable number, arranged at suitable distances apart around the center of motion within the socket C. I prefer to make these springs simply of pieces of india-rubber; but any equivalent may be employed. In order to retain them securely in place, I prefer to set them in sockets d d, formed either in the foot or ankle portion, or both, so as to retain them securely in place under all circumstances. These sockets I make of somewhat larger diameter than that of the springs, so that, as the latter expand by compression, space is left for such expansion; and I also bore or form them at an angle slightly outward from the line of the center of motion, as indicated in Fig. 1, so as to compensate for the inward tendency of the pressure of the bearing D upon the springs. Otherwise, if the springs were set parallel with the line of the center of motion, the turning action of the bearing in pressing down would produce a rubbing action

on the springs, and tend to injure them. The size of the sockets is also so relatively arranged with the springs that when the latter are depressed in any one direction they will be allowed to sink therein till the bearing D on that side comes in contact with the floor of the socket, and they are thus secured from unnecessary pressure.

In adjusting the springs to the right position to receive the pressure of the leg properly I employ small disks or thicknesses *f f* Fig. 6, of buckskin or equivalent, which are placed in the sockets of the springs beneath them. They are also to be employed in adjusting the springs if the springs should become shorter by wear or use. By this means the springs can be adjusted at any time and in the exact degree desired.

The advantages of a series of springs arranged as above described are obvious. All undue rigidity is obviated. Each spring acting independently, the elasticity that is produced is equable and uniform. This also secures a greater degree of elasticity than could be otherwise produced when the pressure is applied in any given direction. If the pressure is applied on any one side the springs yield only on that side, the opposite springs being passive.

It will be seen that I am also enabled to adapt the amount of elasticity to the necessities of the case. For instance, if the pressure is great, a larger number of springs may be employed; if it is small, a portion of the springs may be removed. Thus I can adapt the arrangement for heavy or light use by simply employing a greater or less number of springs; also by using larger or smaller springs. The sockets *d d* are especially adapted to this purpose, as they are made of larger size than the springs, and the latter merely rest in them. This arrangement of the springs enables the wearer to adjust the motions of his leg to suit his particular manner of walking, as he can increase or diminish the rapidity of motion by the inserting or removing of the buckskin disks beneath the springs. In this arrangement the springs are employed in connection with a universal-joint action of the foot and leg, resting laterally as well as longitudinally between the members. The links E E, constituting the center of motion, simply connect the parts, and by sliding one on the other, allow the leg to yield downward a certain degree when pressure is applied. In this manner there is no rigid ankle-joint, but the

springs themselves constitute the joint and insure a free and easy action.

The toe-joint *h* is held in its socket by means of bolts *i i* connecting therewith in any suitable manner, and secured to the foot by nuts *k k*. At a suitable position a plate, H, is attached to the bottom of the toe-piece near the joint, as shown in Fig. 3. This plate has a bearing, *l*, below the joint, with which hinges a bolt, *m*, passing back and connecting with a rubber or equivalent spring, I, by which the proper reaction is produced. By this arrangement it will be perceived that the leverage over the joint of the toe by means of the bolt *m* is considerable and sufficient at all times to produce the necessary action of the parts. This advantage is attained in a great degree by the employment of the plate H, which is situated at the outside of the toe.

A depression or cavity, *p*, is made at the top, between the toe and foot piece, of sufficient depth to allow the necessary movement of the toe, and a projection, *q*, of the foot is made to project over the toe-piece, as represented in Fig. 1, to such a degree as to cover it when straightened. By this means the space between the toe and foot is not left open, and there is no necessity of covering it with buckskin, as usual, but the whole is compact and fits tightly, and therefore the boot worn upon the foot will present a natural appearance.

What I claim as my invention, and desire to secure by Letters Patent, is—

1. A set of springs, G G, in combination with the leg A and foot B, forming a universal joint, substantially as specified.

2. Arranging the series of springs G G near the periphery of the socket C, surrounding the center of motion, in such a manner that the central space will be left open when said springs are employed between the foot and leg to produce reaction by compression, substantially as described.

3. The arrangement of the plate H, provided with the bearing *l* and the bolt *m*, connecting with the spring I, when used in combination with the toe-joint *h* in such a manner as to work over it and produce the necessary leverage, substantially as set forth.

In witness whereof I have hereunto signed my name in the presence of two subscribing witnesses.

DOUGLAS BLY.
